(57) **CLAIM**

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The unshaded region between the oval opening and the bladder forms no part of the claimed design. The broken lines depicting the remainder of the shoe form no part of the claimed design.
